Primary Examiner — Robert M. Spear*Assistant Examiner* — Darcey E Heflin(74) *Attorney, Agent, or Firm* — Carter, DeLuca, Farrell & Schmidt, LLP(57) **CLAIM**

The ornamental design for a skewer, as shown and described.

DESCRIPTION

FIG. 1 is a perspective view of a skewer in accordance with the present design;

FIG. 2 is a top plan view thereof;

FIG. 3 is a bottom plan view thereof;

FIG. 4 is a front side elevational view thereof;

FIG. 5 is a rear side elevational view thereof;

FIG. 6 is a right side elevational view thereof; and,

FIG. 7 is a left side elevational view thereof.

The broken lines shown are included for the purpose of illustrating a portion of the skewer that forms no part of the claimed design.

1 Claim, 4 Drawing Sheets---
